UNITED STATES PATENT OFFICE

169,356

JEWELRY DISPLAY BOX

George F. Brown, Cattaraugus, N. Y., assignor to Warner Jewelry Case Company, Buffalo, N. Y.

Application June 17, 1952, Serial No. 20,234

Term of patent 7 years

(Cl. D80—5)

To all whom it may concern:

Be it known that I, George F. Brown, a citizen of the United States, residing at Cattaraugus, State of New York, have invented a new, original, and ornamental Design for a Jewelry Display Box, of which the following is a specification, reference being had to the accompanying drawings forming a part hereof.

Fig. 1 is a front perspective view of a jewelry display box showing my new design;

Fig. 2 is a front perspective view in an open position;

Fig. 3 is a rear perspective view.

I claim:

The ornamental design for a jewelry display box, as shown.

GEORGE F. BROWN.
